UNITED STATES PATENT OFFICE.

ORVILLE L. PARMENTER, OF RACINE, WISCONSIN.

PAPER RECEPTACLE.

SPECIFICATION forming part of Letters Patent No. 683,789, dated October 1, 1901.

Application filed January 26, 1901. Serial No. 44,879. (No model.)

To all whom it may concern.

Be it known that I, ORVILLE L. PARMENTER, a citizen of the United States, residing at Racine, county of Racine, State of Wisconsin, 5 have invented certain new and useful Improvements in Paper Receptacles; and I do hereby declare the following to be a full, clear, and exact description of the invention, such as will enable others skilled in the art to 10 which it appertains to make and use the same.

This invention relates to certain improvements in paper or equivalent fabric articles, and more particularly to envelops, receptacles, or bags or like articles; and the objects 15 and nature of my invention will be understood by those skilled in the art in view of the following explanations of the constructions shown in the accompanying drawings merely as examples for the purposes of description among other forms within the spirit and scope of my invention.

My invention consists in certain novel features in construction or in combinations or in arrangements of parts, as more fully and 25 particularly pointed out and described hereinafter.

Referring to the accompanying drawings, Figure 1 is a plan view of a series of parallel independently-formed paper tubes secured 30 on a backing-sheet, dotted lines indicating the transverse fold-line and the separating-lines between the tubes in the series of completed receptacles. Fig. 2 is a sectional view taken in the plane of the line 22, Fig. 1, dotted 35 lines showing the transverse fold-line. Fig. 3 is a cross-section on the line 33, Fig. 1, showing the tubes partially distended to more clearly illustrate the construction. Fig. 4 is a perspective view illustrating a portion of the sheet of tubes of Fig. 1 in the act of being 40 folded upon itself on the transverse fold-line to form the complete connected and detachable receptacles. Fig. 5 is a perspective view of a plurality or sheet of the completed 45 receptacles open and ready for filling and sealing. Fig. 6 is a perspective view of one of the receptacles of Fig. 5 detached from the sheet and shown in the act of being sealed, the sealing-flap and upper projecting 50 tube end being folded or doubled over and down. Fig. 7 is a perspective view of one of said receptacles detached, sealed, and re-

versed, and illustrating the manner of opening the same, the receptacle being shown partially opened, dotted lines indicating a finger 55 in the act of tearing open the receptacle. Fig. 8 is a perspective view of the receptacle of Fig. 7, showing the same after opening. Fig. 9 is a perspective view of a sheet of the connected receptacles so formed that in sealing the open ends thereof one end of a tube is not doubled over the other end thereof 60 with the flap. Fig. 10 is a vertical or central section, enlarged, through the sealed receptacle shown in Figs. 5 and 6. Fig. 11 is 65 a cross-section, enlarged, of the receptacle of Fig. 10. Fig. 12 is a perspective view of a detached receptacle of a modified construction, the tube being shown extending only a short distance along the front wall or ply of 70 the backing, and thereby forming each receptacle with only one compartment, parts being broken away and the front wall swung out.

Among other features this invention comprises a sheet or plurality of detachably-connected receptacles, each having a mouth end and a flap to seal the same and the opposite closed end so formed as to permit easy opening thereof to gain access to the interior of 75 the sealed receptacle.

Receptacles within the spirit and scope of my invention can be manufactured according to various methods and either individually or in sheets or series and of various constructions and forms. As at present advised by experience, however, I prefer to manufacture the same in sheets or series of detachably-connected receptacles.

I illustrate simple constructions within the 90 spirit and scope of my invention and a simple and economical method of manufacturing the same, although I do not desire to limit my invention thereto.

In the drawings, 1 is a backingsheet or wall, 95 usually formed of strong and comparatively heavy paper or any other suitable material and of necessary size and dimensions to form the front and rear walls and sealing-flaps of a plurality of the receptacles.

2 is a tube formed, preferably, of a sheet of comparatively thin flexible paper or other suitable material folded to form a front wall, two collapsible sides, and a rear wall. The

collapsible sides 2' can be longitudinally folded or creased inwardly to permit flattening of the tube or expansion thereof to a shape approximately rectangular in cross-section, although I do not desire to limit my invention in this regard. A plurality of the tubes 2 are arranged longitudinally on the sheet 1 parallel with each other and comparatively close together, so that the tubes extend from one edge of the sheet almost to the opposite edge, leaving the projecting sealing-flaps herein-after referred to. Each tube is independently secured on the sheet in any suitable manner, as by being pasted or cemented thereto. On lines between the tubes and parallel with their longitudinal edges I form the sheet 1 in any suitable manner to constitute dividing or separating lines 1', extending from edge to edge of the sheet. These separating-lines or lines of weakness can be formed in any suitable manner, as by rows of cuts, slits, perforations, or scoring, or otherwise to render the backing-sheet or front and rear walls separable on lines between the tubes or receptacles, as hereinafter set forth. The backing-sheet, with the row of tubes thus secured thereon, (see Fig. 1,) is then folded on itself on the transverse fold-line 1", (see Fig. 4,) and the end portions of each tube are suitably secured together to produce the finished device about as shown in Fig. 5, wherein a series of detachably-connected receptacles are formed having the backing-sheet forming the front and rear walls thereof and each having two compartments with open-top mouths and closed at their lower ends by the doubled or folded portion of the tube.

The sheet of parallel tubes, as shown in Fig. 1, is preferably formed with a transverse separating-line or a line of weakness, which constitutes the transverse fold-line 1". This line 1" can be formed by perforations through the tubes and backing-sheet, or by slits or scoring, or possibly in other ways or by other means. When the said sheet of tubes is folded on itself, as hereinbefore described, along said line 1", said line of weakness is located across the lower extremity of the sheet or plurality of receptacles shown in Fig. 5 for the purposes hereinafter set forth. I generally so locate the said fold-line 1" that when the sheet of Fig. 1 is folded upon itself with its opposite plies parallel with each other one end of each tube will extend above and beyond the opposite end thereof, as clearly seen in Fig. 5. Between each pair of separating-lines 1' the backing-sheet is extended to form the independent sealing-flaps 3. Each flap extends beyond the tube ends and preferably has paste or cement or other adhesive substance applied thereto, as shown. It will thus be understood that each receptacle as so far described comprises a single sheet forming the front and back wall, the sheet extended at the back to form a sealing-flap, and that between and secured to and folded with said sheet is located a tube folded

to form the two plies or lengths parallel with each other and secured together at their adjoining or meeting walls, with one extending above the other, thereby forming a receptacle with two pockets or compartments. The receptacle is closed by folding the rear wall of the backing-sheet and the rear projecting end of the tube (see Fig. 6) forwardly over the front end of the tube and then down and in against the front wall, to which the sealing-flap is cemented, thereby closing and sealing the receptacle, as shown in Figs. 7 and 10. This form of the receptacle is thus closed and reinforced at the upper end by several thicknesses—viz., the backing-sheet and one end of the tube—and the lower end is also of several thicknesses where folded or doubled—viz., the backing-sheet and tube.

Usually I do not secure the adjoining walls of the tube together near the lower or doubled end thereof, so that the sealed receptacle can be easily opened by inserting the finger (see Fig. 7) or any suitable instrument between the two plies of the tube at the doubled or folded portion thereof, and then by applying the necessary pressure the plies of the tube and backing-sheet are torn apart and separated from each other along the weakened or separating line 1", so that the receptacle will open, as shown in Fig. 8, opening the two plies at the lower end thereof and exposing and permitting removal of the contents thereof. When thus opened, the device forms a convenient receptacle for carrying in the pocket to receive various slips, paper money, &c.

These receptacles can be sold in sheets or series composed of any convenient number of the detachably-connected receptacles, each of which can have advertising matter and directions for sealing and opening and other matter imprinted thereon.

The receptacles are of peculiar advantage when employed as pay-envelops. The folded paper money can be slipped in one compartment of a receptacle and the coins in another compartment, and the bookkeeper can easily fill all the envelops of a series and then seal them simultaneously and then detach them for distribution, and the reinforced ends of each receptacle renders the same exceedingly strong and durable for this purpose. After the employee has opened the receptacle it forms a convenient device in which to carry the money in the pocket.

The receptacles can be economically manufactured, and waste of paper in the process of manufacture is reduced to a minimum. However, I do not wish to limit all features of my invention to the receptacles made in sheet or connected form, nor to the peculiar tube shown in the figures of the drawings hereinbefore referred to, as the pocket or pockets of each receptacle can be otherwise formed by a sheet or sheets secured to the backing-sheet; nor do I wish to limit my invention to forming the receptacle with a

5 pocket or pockets formed with the creased or bellows sides, nor to forming a series of connected receptacles comprising independently-formed or independently-secured tubes. Also
 10 I do not wish to limit my invention to the feature of continuing one tube across the fold-line, as the two pockets might be formed by separate tubes extending to the fold-line of the sheet; nor do I limit my invention to
 15 the reinforced top seal by folding over the projecting end of the tube, as the transverse fold-line 1" can be so arranged that the two ends of each tube will end in the same plane without projecting one above the other, as
 20 shown in Fig. 9. In this form the flap alone will fold over the mouths of the two pockets and hold the upper end of the receptacle compressed and sealed. Also I do not wish to limit my invention to a receptacle having
 25 two pockets, as the device might be formed about as shown in Fig. 12 without one ply of the tube extending up the full length of the front wall or ply of the backing-sheet. In this form the tube can extend a short dis-
 30 tance beyond the fold-line 1", and the lower end of the pocket will be closed by the lower end of the tube doubling up with the front wall of the backing-sheet, and the front wall of the backing-sheet will be secured directly
 35 to the front wall of the tube forming the single pocket. This form of receptacle can be sealed according to any of the methods or ways hereinbefore described or otherwise within the spirit and scope of my invention.
 40 45 It is evident that various changes might be made in the forms, constructions, and arrangements of the parts described without departing from the spirit and scope of my invention and that in all instances it may not be necessary to use an integral sealing-flap or to extend the backing-sheet up the full lengths of both the front and rear of the receptacle; but I desire to cover all such changes as fall within the spirit and scope of my invention.

Having thus fully described my invention, what I claim as new, and desire to secure by Letters Patent of the United States, is—

1. A sheet of detachably-connected receptacles, comprising a backing-sheet for all the receptacles having weakened separating-lines between the receptacles and a weakened fold-line traversing all the receptacles, each receptacle having a mouth and sealing-flap at 55 one end and said weakened fold-line at the opposite end along which the receptacle can be opened when sealed at its mouth, substantially as described.

2. A pay-envelop comprising a backing-sheet doubled on a transverse fold-line, a receptacle secured between the two plies of said sheet and at one end closed by the doubled portion of said sheet and having a mouth at the other end projecting beyond the 65 edge of one ply of said sheet, the other ply of said sheet extended to form a sealing-flap, whereby said projected end of the receptacle

folds over with said flap onto the outer face of the backing-sheet to seal the receptacle, said receptacle formed to be opened along 70 said doubled portion, substantially as described.

3. A receptacle comprising a double backing-sheet having a series of pockets formed between and secured to its plies, said sheet 75 separable on lines between the pockets, each pocket formed with a mouth at one end thereof, the opposite end thereof closed at the folded or doubled portion of the backing-sheet, means to seal the pockets and close said 80 mouths, said backing-sheet formed with a single weakened or separating line along said doubled portion and traversing all said pockets, each pocket formed at the doubled end for the insertion of the finger within the fold, 85 for the purpose described.

4. A receptacle comprising a doubled backing-sheet, a pocket between and secured to the two plies of said backing-sheet and having its inner end closed by being doubled 90 with said sheet on a single fold-line, the pocket having a mouth at its opposite end, and means to close the same, the backing-sheet and pocket having weakened or separating lines along the fold-line at the doubled 95 end thereof, the plies of the pocket at its doubled portion disconnected to permit insertion of an instrument or the finger for separating the parts along said lines for opening the receptacle, substantially as described. 100

5. A receptacle comprising a backing-sheet doubled along a transverse weakened fold-line to form the front and back walls of the receptacles, two parallel pockets between and secured to said front and rear walls and 105 having mouths at their upper ends and having their lower ends closed at the doubled portion of the sheet, means to seal together the free ends of the sheet and thus close the mouths of the pockets, the receptacle formed 110 with a recess or opening extending through from edge to edge of the receptacle between the inner ends of the pockets for the insertion of a finger or instrument for separating the parts along the fold-line and thus open 115 the pockets at their lower ends, substantially as described.

6. A sheet or series of receptacles comprising a backing-sheet, a series of parallel tubes secured on one face of the sheet, the sheet 120 being separable on lines between the tubes, the sheet being doubled on itself on a single weakened fold-line traversing the sheet and intermediate portions of all the tubes, the two plies of each tube secured together at 125 their inner walls, one end of said sheet being extended to form sealing-flaps extending beyond the tube ends, whereby each receptacle has two pockets closed by the doubled portion of the tube on and severable 130 along the single transverse fold-line, substantially as described.

7. A sheet of detachably-connected receptacles comprising a backing-sheet a series of

parallel tubes or pockets secured thereto, a single weakened transverse fold-line extending across said sheet and intermediate portions of all said pockets, said sheet and pockets being doubled or folded on each other on said single fold-line, thereby forming each receptacle with two compartments closed at their lower ends by said single fold, the inner walls of the two plies of each pocket secured together, and means to close and seal the mouths of the compartments of each receptacle, whereby the opposite ends of each compartment can be opened by severing the material along said single fold-line, substantially as described.

8. A receptacle consisting of a doubled backing-sheet forming the front and rear walls of the receptacle, a tube secured to and between said walls and doubled therewith at the fold-line thereof, one end of said sheet extended to form a sealing-flap, and one end of said tube extended and adapted to fold over with said flap in closing the mouth of the receptacle, substantially as described.

9. A receptacle comprising a backing-sheet, a tube secured thereto, said sheet and tube folded or doubled on a transverse fold-line and the two parallel plies of the tube secured together forming two pockets with mouths at their upper and their lower ends closed by the doubled portion, one end of the backing-sheet extended to form a sealing-flap and one end of the tube extended beyond the other to fold over with the flap in closing the mouths of the pockets, substantially as described.

10. A plurality of connected receptacles comprising a backing-sheet and a series of parallel tubes secured thereon, said backing-sheet folded or doubled along a transverse weakened fold-line, the adjoining walls of

the tubes of each receptacle secured together to form each receptacle with two pockets, the lower portions of the adjoining walls of the tubes disconnected, the backing-sheet separable on lines between the tubes, and each receptacle provided with means to seal its upper end, substantially as described.

11. A sheet having a series of parallel tubes secured thereon, said sheet and tubes doubled together on a transverse weakened fold-line traversing intermediate portions of the tubes, the two plies of each tube secured together at their inner walls, the inner walls of said tube-plies disconnected near said fold-line, substantially as described.

12. A sheet of detachably-connected receptacles, comprising a backing-sheet folded or doubled on itself along a weakened fold-line to close the inner ends of the pockets, and sealing-flaps for closing the opposite ends of the pockets, each receptacle having a space at its doubled end along said weakened fold-line for the insertion of a finger to sever the same on said line, substantially as described.

13. A pay-envelop comprising a backing-sheet doubled on itself on a single weak separable fold-line, pockets secured to and between the plies of said sheet and at their inner ends closed by the doubled end thereof, said pockets secured together at their inner walls, said sheet extended at one edge to form a sealing-flap to close the open ends of the pockets, whereby the pockets can be opened at their inner ends by separation on said fold-line, substantially as described.

In testimony whereof I affix my signature in presence of two witnesses.

ORVILLE L. PARMENTER.
